ELECTRICAL ACCESSORY APPARATUS

Sidney W. Edlund, Brooklyn, N. Y.

Application June 30, 1928, Serial No. 289,375

9 Claims. (Cl. 173—343)

This invention relates to electrical accessory apparatus, and refers particularly to separable attachment plugs or parts thereof. It is well understood that the usual separable attachment plug consists of a base having electrical contacts therein, and a cap member carrying prongs which are introduced into the base and moved into engagement with the base contacts. It has been the recent practice in building construction to permanently install in the floor, or base boards or walls, the equivalent of the base of such a plug. This permanent base, through practice, has oftentimes been termed, a socket. Herein, it will be understood that the term "base" will be employed to denote the regular base of a plug or the so-called permanent base.

The bases for the plugs are sometimes located in positions not readily accessible, often being back of articles of furniture, etc., and for this reason, among others, it is usually difficult to insert the prongs of the cap into the base, both by reason of its inaccessibility as well as by reason of the fact that in such places sufficient light is not usually available to see the base properly.

The difficult assembly has hitherto arisen because plugs have thus far not been made with any particular or improved construction which would permit the prongs to be readily guided into the slots of the base when the person attempting the assembly brings the prongs in contact with the free or exposed surface of the base. Attachment plugs now in use are of three general types, and when the base of any of these plugs cannot be clearly seen the same difficulty of assembly exists. The first type is one in which the exposed surface of the base is flat; hence the chance of getting the prongs in proper alignment on the first attempt of assembly is very small. The second type of plug has provided a very small taper at the edges of the slots, but even with this type, portions of the free surface are flat and consequently there is no assurance of proper guidance of the prongs into the slots once the two prongs engage any points of the free surface. The third type has the area of the surface immediately around the slots recessed or hollowed out. This construction is of advantage only when the prongs happened to come in contact with the surface within the recessed area, and this type requires a special construction of the ends of the prongs.

It is the object of this invention to produce an improved plug with special reference to the construction of the free surface and the ar-

angement of the slots therein, so that the only requirement of the person assembling the cap with the base is to bring both of the prongs into any contact with the free surface, and thereafter by a slight manipulation of the prongs have them guided into the slots.

Further and more specific objects, features and advantages will more clearly appear from the detailed description given below when taken in connection with the accompanying drawing which forms part of the specification, and which illustrates the preferred embodiments of the invention.

In the drawing Fig. 1 is a perspective view of a plug embodying the invention with a prong-carrying cap shown in relation thereto.

Fig. 2 is an elevational view of the plug with the end surface thereof in section.

Fig. 3 is a perspective view, similar to Fig. 1, showing an arrangement of slots and prongs at angles to each other.

Fig. 4 is a perspective view, similar to Fig. 1, showing the base with slots of the "universal" type.

Fig. 5 is an elevational view, similar to Fig. 2, of the form of plug shown in Fig. 4; and

Fig. 6 is a partial perspective view of a lamp, the base of which is provided with prongs to be inserted in a base of the type shown in Figs. 3 and 4.

A preferred embodiment of my invention is shown in Figs. 1 and 2 and comprises a plug having a body portion 10 of standard construction to be screwed into a socket. This body portion is generally of insulating material and has a top or free portion 11 of insulating material. This portion 11 is provided with an end or free surface 12 having prong-guiding slots 13 and 14 therein. These slots are spaced apart and lead to the usual chambers beneath the free surface. Within the 40 chambers are disposed, in the usual manner, contact members with which engagement is made by prongs 15 and 16 suitably carried by a cap member 17 which is provided with a bore 18 through which a cable, not shown, may pass.

Referring particularly to Figs. 1 and 2, it will be seen that the free surface 12 has a generally concave curvature which begins at the very edge of the surface and slopes downwardly and inwardly throughout toward the center adjacent which the slots 13 and 14 are located. There preferably is provided at the center a raised hump, the construction and function of which will be later described. Consequently, it will be observed, there are no flat portions on this free surface,

and when a pair of prongs are brought anywhere into contact with this free surface and are both within the periphery of the edge, they will be guided to the slots.

5 The construction of the hump preferably has a central upper edge or ridge 19 and lateral surfaces 20 and 21 sloping gradually therefrom in opposite directions toward the adjacent slots 13 and 14. From Fig. 2 it will be seen that this ridge 10 line 19 is preferably for a substantial part of its length on a level with the edge of the main surface 12, but that at its ends 22 and 23 the ridge 19 is curved downwardly. The construction is such that where the main surface joins the ends 15 and sides of the hump, smooth curves result. Preferably the distance between either slot and the nearest portion of the edge of the main surface is designed to be less than the distance between the slots. Also the distance between the 20 ridge 19 and the edge of the main surface along a line drawn across the slots is preferably designed to be greater than the distance between the slots and therefore greater than the distance between the prongs. This construction requires 25 that the prongs upon a slight movement shall immediately be guided into the slots. In some few instances the manipulator of the cap may accidentally move one of the prongs over the edge of surface 12, and before proper assembly is accomplished this prong must be returned to the free 30 surface 12.

In Figs. 3, 4 and 5 the construction is essentially the same, except that the slots 24 and 25 in Fig. 3 are disposed at right angles to each other 35 to receive similarly disposed prongs 26 and 27 on a cap 28. In Figs. 4 and 5 the slots 29 and 30 are of the T shape or "universal" type to permit engagement with the base of any arrangement of prongs. In Fig. 6 prongs 31 and 32 extend 40 from the base 33 of a lamp 34 and are adapted to engage with either of the plugs shown in Figs. 3 and 4.

Referring to Fig. 1, it will be apparent that as long as the prongs are brought into contact with 45 the main or free surface of the base the relative position of the prongs at the instant of contact is immaterial. The inward and downward curvature of the main surface will tend to keep the prongs within that area and then a slight turning movement of the prongs will cause them to 50 slip downwardly along the above-mentioned surfaces and readily find the slots. If prongs disposed at right angles to each other are employed, and upon the first turning thereof it is found 55 that a prong has encountered the wrong slot, it merely requires a half turn in either direction to bring the prongs into alignment with the proper slots without removing them from contact with the surface.

60 While there has been described in detail a particular improvement and in respect to a preferred form thereof, it is understood that the invention is not to be limited to such details or form since many changes and modifications may be 65 made and the invention may be embodied in widely different forms without departing from the spirit and scope in the broader aspects. Hence it is desired to cover all modifications and forms coming within the language or scope of 70 any one or more of the appended claims. What is claimed as new and desired to be secured by Letters Patent, is:

1. A base for the reception of an attachment cap, said base having its free surface provided 75 with slots for the reception of prongs carried by

said cap and having each part of the entire area of said surface sloping downward toward one or the other of said slots.

2. A base for the reception of an attachment cap, said base having its free surface provided 5 with slots for the reception of prongs carried by said cap and having each part of the entire area of said surface sloping inwardly and downwardly from its outer edge, the distance between any slot and the nearest portion of the edge being less than the distance between the slots. 10

3. A base for the reception of an attachment cap, said base having its free surface provided 15 with slots for the reception of prongs carried by said cap and having each part of the entire area of said surface sloping inwardly and downwardly from its outer edge toward its center, and a prong-guiding partition extending across said surface between the slots.

4. A base for the reception of an attachment 20 cap, said base having its free surface provided with slots for the reception of prongs carried by said cap and having each part of the entire area of said surface sloping inwardly and downwardly from its outer edge toward its center, a prong- 25 guiding partition extending partially across said surface between the slots, the lateral surfaces of said partition sloping toward the adjacent slots.

5. A base for the reception of an attachment cap, said base having its free surface provided 30 with slots for the reception of prongs carried by said cap and having each part of the entire area of said surface sloping inwardly and downwardly from its outer edge toward its center, and a prong-guiding partition extending partially across said surface between the slots, the lateral surfaces of said partition sloping toward the adjacent slots, the ridge of said partition near its 35 ends sloping downwardly toward the main surface. 40

6. A base for the reception of an attachment cap, said base having its free surface provided 45 with slots for the reception of prongs carried by said cap and having each part of the entire area of said surface sloping inwardly and downwardly from its outer edge toward its center, and a prong-guiding partition extending part of the length across said surface between the slots, the lateral surfaces of said partition sloping toward the adjacent slots, the ridge of said partition near its 50 ends sloping downwardly toward the main surface, the center portion of said ridge being substantially level with the edge of the main surface. 55

7. A base for the reception of an attachment cap, said base having its free surface provided 60 with slots for the reception of prongs carried by said cap and having each part of the entire area of said surface sloping inwardly and downwardly from its outer edge toward its center, and a prong-guiding partition extending partially across said surface between the slots, the lateral surfaces of said partition sloping toward the adjacent slots, the ridge of said partition near its 65 ends sloping downwardly toward the main surface, the center portion of said ridge being substantially level with the edge of the main surface, the lateral and end surfaces of said partition and the main surface of the plug joining in smooth curves. 70

8. A base for the reception of an attachment cap, said base having its free surface provided 75 with slots for the reception of prongs carried by said cap and having each part of the entire area of said surface sloping inwardly and downward-

ly from its outer edge toward its center, and a prong-guiding partition extending partially across said surface between the slots, the lateral surfaces of said partition sloping toward the adjacent slots, the ridge of said partition sloping toward the adjacent slots, the ridge of said partition near its ends sloping downwardly toward the main surface, the center portion of said ridge being substantially level with the edge of the main surface, the lateral and end surfaces of said partition and the main surface of the base meeting in smooth curves, the distance between each slot and the nearest portion of the edge of the plug being less than the distance between said slots.

9. An attachment plug comprising a base portion having a free surface with prong-receiving slots therein, the entire area of said surface sloping inwardly and downwardly from its outer edge toward its center, and a prong-guiding par-

tition extending across said surface between the slots, the lateral surfaces of said partition sloping toward the adjacent slots, the ridge of said partition near its ends sloping downwardly toward the main surface, the center portion of said ridge being substantially level with the edge of the main surface, the lateral and end surfaces of said partition and the main surface of the base meeting in smooth curves, the distance between each slot and the nearest portion of the edge of the plug being less than the distance between slots, the distance between the ridge of said partition and the edge of the base along a line across the slot being greater than the distance between slots.
